GOBLET

John T. Dowd, Aldan, Pa.

Application December 17, 1951, Serial No. 17,758

Term of patent 14 years

(Cl. D36—8)

To all whom it may concern:

Be it known that I, John T. Dowd, a citizen of the United States, residing at Aldan, Delaware County, Pennsylvania, have invented a new, original, and ornamental Design for a Goblet, of which the following is a specification, reference being had to the accompanying drawing, forming a part hereof, in which:

Fig. 1 is a perspective view of a goblet showing my new design;

Fig. 2 is a perspective view showing the goblet with the cover removed;

Fig. 3 is a view in perspective of the cover member showing the same in inverted position;

Fig. 4 is an elevational view of the goblet; and Fig. 5 is an enlarged sectional view on line 5—5, Fig. 4.

I claim:

The ornamental design for a goblet, substantially as shown.

JOHN T. DOWD.
